UNITED STATES PATENT OFFICE.

RICHARD M. HOPKINS, OF RUTHERFORD, NEW JERSEY, ASSIGNOR TO AMERICAN DISTRICT TELEGRAPH COMPANY, OF JERSEY CITY, NEW JERSEY, A CORPORATION OF NEW JERSEY.

REGISTRY SYSTEM AND REGISTER THEREFOR.

1,394,834.

Specification of Letters Patent.

Patented Oct. 25, 1921.

Application filed June 12, 1919, Serial No. 303,632. Renewed April 28, 1921. Serial No. 465,249.

To all whom it may concern:

Be it known that I, RICHARD M. HOPKINS, a citizen of the United States of America, and resident of Rutherford, in the county of Bergen and State of New Jersey, have invented a Registry System and Register Therefor, of which the following is a specification.

My invention relates to improvements in watchmen's registry systems, by which term I mean systems in which the visits of watchmen to certain stations which they are supposed to visit regularly, are registered, and embodies improvements in the system for the same purpose set forth in the application of C. C. Johnson, Sr., No. 209,279, filed Dec. 28, 1917. According to the said Johnson system, the watchman is provided with a so-called "box" containing registry mechanism intended to be actuated by a push-button which the watchman may press each time he reaches a station which he is supposed to visit; but this registry mechanism is normally locked, and cannot be actuated, except and until the watchman applies a certain portion of his box to a key device, or "conditioning device," of which there is one at each station to be visited. When the box has been so applied to a key device (preferably, means are provided whereby on each occasion only one particular key device may be so used) then the push button may be actuated and the visit of the watchman to that station thereby registered. The several key devices are preferably provided with means whereby they are differentiated one from another, and the mechanism of the box is provided with corresponding differentiating mechanism of such nature that actuation of the registering mechanism of the box at one station conditions that mechanism for release upon application to the next key device of the series, and upon application to the said next key device only. In this way the watchman is compelled to visit the several stations in regular order, and cannot continue to actuate his registering mechanism if he omit any station in making his tour, or if he visit the stations out of order. When the watchman reaches the end of his tour he may connect suitable transmitting mechanism within his box to a suitable circuit, or, alternatively, may connect his box to suitable stationary transmitting mechanism, and may then send

through such circuit a signal indicating that he has completed his tour. In this way it is rendered unnecessary for the watchman to signal to the central station separately for each visit to each of his stations; one signal sent at the conclusion of each tour showing that he has visited all of the stations in that tour.

If the key devices of the several stations to be visited may be divided into groups of a relatively small number each, in which groups the characteristics by which each key device of the group is differentiated from all the others of that group may be repeated, some other feature being provided to differentiate all of the key devices of any one group from all of the key devices of all the other groups, then the construction of the said key devices may be simplified; and, what is still more important, so may the construction of the locking device of the box itself be simplified, and at the same time it is possible to adapt the box for registering visits to a very much greater number of stations than would otherwise be practicable.

My invention consists in means whereby key devices so arranged in groups, with individual differentiation within each group and differentiation between groups, may be employed in a registry system such as referred to; in improved means whereby the watchman may actuate his registry mechanism once only at each visit to any one key device; and in various other features, all as herein-after described and particularly pointed out in the appended claims.

The object of my invention is to improve and simplify the key devices and watchmen's registry apparatus of registry systems such as referred to. Other objects, more detailed in nature, will appear hereafter.

I will now proceed to describe my invention with reference to the accompanying drawings, illustrating one embodiment thereof, and will then proceed to point out the novel features in claims. In said drawings:

Figure 1 shows a side elevation of the mechanism of a watchman's box and corresponding key device, applied to one another, the usual inclosing case of the box being omitted, and certain minor parts being broken away or shown in section.

Figs. 2 and 3 are corresponding detail

perspective views, Fig. 2 showing one of the key devices, with a portion of the base thereof broken away, and Fig. 3 showing the corresponding front portion of the watchman's box.

Fig. 4 shows a top view of the mechanism of the box, and of a key device to which that box is shown as applied. Fig. 5 shows a transverse sectional elevation of the mechanism of the box, taken on the irregular section line 5—5 of Fig. 4.

Figs. 6—10 inclusive are detail views, Fig. 6 showing a detail elevation, on a plane parallel to that of Fig. 5, of the ratchet device for actuating the registering mechanism of the box, Fig. 7 a perspective elevation of the same device, Fig. 8 a further perspective elevation of the same device with certain parts in a different position, Fig. 8^a a detail view of a portion of cam 19, Fig. 9 a more or less diagrammatic view showing the break wheel and pens of the transmitter of the box, and associated parts, together with diagrammatic representations of a plug and socket by which the pens may be connected to a transmitting circuit; and Fig. 10 is a detail sectional elevation showing the transmitter gear train and associated parts.

Fig. 11 is a detail perspective elevation of a portion of the mechanism for winding the driving spring of the transmitter; Fig. 12 is a detail perspective elevation of the automatic resetting device of the registry mechanism; Fig. 13 is a detail sectional elevation of a portion of the registry mechanism; and Fig. 14 a circuit diagram.

In the drawings, A designates a key-device, or watchman's box conditioning device, such as referred to, and B the watchman's box or register to be carried by the watchman and by him engaged to each key-device in turn. For insuring proper relative engagement of the box with each key-device, any suitable means may be provided; the particular arrangement for the purpose shown consisting of tubular sockets B^b on the box adapted to receive pins A^a with which each key-device is provided. As to any one box and corresponding series of key-devices, these pins A^a and sockets B^b do not constitute part of the means for differentiating one key-device from another; but of course each box and corresponding series of key-devices may have a different arrangement of pins A^a and sockets B^b.

Each key-device A comprises a plurality of what may be termed "key-shanks", 1, with ends suitable for engaging the ends of corresponding levers or tumblers 10 of the box and for lifting out of engagement with a notched lock-wheel 15 any tumblers 10 which may be in engagement with that lock-wheel. The positions of the notches of this wheel, and the arrangement of the key-shanks of the various key devices are such,

relatively, that for any one position of wheel 15 only one certain key-device of each group or tour will release all of the tumblers 10 from that wheel. From this it follows that application of the box to any proper key-device of a tour, and operation of the registry mechanism of the box thereat, conditions the box for application to and operation at the next key-device of the series, and that next key-device only. In other words, the watchman must visit each station in turn, and in proper order, and at each station must correctly operate the registry mechanism of his box, else he cannot fully engage his box with the next key-device of the series or operate the registry mechanism thereat.

The watchman, having correctly engaged his box with a proper key-device, registers his visit to the station and to the key-device thereat by operating the registry mechanism of the box, to which end he presses in a button 17, normally held out by a spring 18. The shank of this push-button carries a pivoted and spring-actuated ratchet-cam 19, a pin 20 of which is adapted to engage the teeth of a ratchet wheel 21, on the shaft 22 of wheel 15, and drivingly connected thereto. As will be explained presently, means are provided whereby improper manipulation of the mechanism of the box by means of the push-button 17 is prevented, and whereby the watchman is compelled to give a full stroke to that push-button each time he operates it, else no registration is effected and the box cannot be operated at the next station.

Motion is communicated, from shaft 22, through gears 23 and 24, to a shaft 26 and thence to a notched lock-wheel 16 on shaft 26 and connected to said shaft by a key 25 which enforces rotation of wheel 16 with that shaft, while permitting longitudinal motion of the wheel on said shaft. In order that the mechanism of the box may not be operated unless, at each presentation to a key-device A, the box B is thrust properly and to the full extent against that key-device, and in order to prevent operation of the registry mechanism except in accordance with the group-differentiation of the key-devices, a locking-bar 27 is provided, among the lock-levers or tumblers 10 of the box, but adapted to have a longitudinal motion; and this bar slides through the notches 28 of wheel 16, but is provided with a notch 29 which, when in registry with that wheel, permits rotary advance thereof as the push-button 17 is pressed in. In other words, in order that the push-button 17 may be pressed in and the registry mechanism operated, at each station, not only must all of the tumblers 10 be lifted clear of wheel 15, but also the notch 29 must be in registry with wheel 16; and this permits automatic adaptation

of the box to group-differentiation of the various groups of key-devices, since wheel 16 occupies a different position, axially, for each separate group of key-devices. At its 5 outer end, bar 27 is provided with a finger 29; and each key-device, A, is provided with a corresponding finger 29^a, adapted to engage the end of finger 29 when the box B is properly applied to such key-device. The 10 fingers 29^a of all of the key-devices of any one group or tour, are of the same length (which length is different from that of the fingers 29^a of all of the other groups or tours); and therefore when the box is properly 15 applied to the several key-devices of any one group or tour, the bar 27 will in each case be moved to the same position, longitudinally, and to a position which will bring its notch 28 into registry with wheel 16, provided the watchman be making the 20 proper tour, *i. e.*, provided the axial position of wheel 16 corresponds to the length of the fingers 29^a of the key-devices of the tour which the watchman is then making. 25 Means for the automatic shifting of the position of wheel 16, axially, at the end of each tour, will be described presently.

Bar 27 has a pivotal, sliding engagement with the pivot-pin 10^a of the lock-levers or 30 tumblers 10, and at its inner end is pivoted to a lever 27^a, having a spring 27^b whereby, as soon as box B is withdrawn from any one of the key-devices, bar 27 is thrust out, so as to bring the body of that bar in engagement 35 with one of the notches of wheel 16, so preventing rotation of that wheel. As explained hereafter, the motion of lever 27^a is utilized for the operation of a species of 40 escapement to prevent more than one effective actuation of the registry mechanism for each proper application of the box to a key-device.

It is intended that the watchman, from time to time, (usually and preferably when 45 he has completed a tour), shall transmit a characteristic signal to some central office or point from which supervision is exercised or at which a record is made of his signals; thereby in effect, registration of 50 the watchman's visits to the several stations is transferred from the box to the central station. To the end that such signals may be transmitted, the box B is provided with transmitting mechanism which, conveniently, 55 may be similar to that of an ordinary so-called "messenger call box," comprising a signal wheel 11 with suitable contact pens 12 and wires leading therefrom to a plug 39 adapted to be inserted into a contact 60 socket C; of which sockets there will be one at the end of each tour, usually, (though if desired the sockets at the ends of some of the tours may be omitted), these sockets being connected by suitable circuits to the 65 central supervising or recording station.

The transmitter may be understood to include the usual driving spring 13, arranged to be wound by a handle 14, also the usual gear train through which that spring may drive signal wheel 11, also the usual regulating device. But in this transmitter, the handle 14 is normally free, and if turned before the registry mechanism has reached a condition corresponding to the last station of a tour, turning such handle 14 does not 70 wind the spring. The shaft 36 of the handle 14 is provided with a pivoted pawl, 36^a, carried on an arm 36^b, and adapted to engage a tooth, 36^c, attached to the first gear, 36^d, of the spring-driven gear train of the 80 transmitter; such pawl, 36^a, being normally held out of engagement with tooth 36^c by spring 36^e. When the last station of any particular tour has been reached the gear 24 will have reached, in its rotation, a position 85 such that an arm 24^a carried by it will engage pawl 36^a and move it into engagement with tooth 36^c. It follows, therefore, that when the watchman has reached the last station in any particular tour, after having 90 visited in regular order all of the other stations in that tour and operated his box thereat, he may apply his plug 39 to the contact socket C at that last station, and may then operate his transmitter by means 95 of the handle 14, and so send in the proper signal.

As previously explained, this watchman's box is intended to be used by a watchman in traversing a plurality of "tours," *i. e.*, groups 100 of stations, in regular order. The key devices A of corresponding stations of the several tours are the same, except as to the length of the fingers 29^a, each tour having 105 fingers 29^a of a particular length which distinguishes the key devices of that tour from the key devices of all of the other tours. The box comprises means for adapting its mechanism, automatically, for the key devices of the tour next to be visited, as the 110 visit to the last key device of a tour is made. To this end, wheel 16 is mounted to be moved axially along its shaft, as already stated, and for so shifting it, a pivoted shifting lever 16^a is provided, said lever having 115 a pin-engagement with a groove in the hub of wheel 16, and having also a pin 16^b in engagement with a worm 16^c on a shaft 16^d driven by gears 16^e from the transmitter gear train; said gears being so proportioned 120 and arranged that one complete transmitting operation rotates the worm sufficiently to move wheel 16 axially to the position which that wheel should occupy, with respect to bar 27, while the watchman is traversing the next tour. Conveniently, said gears are arranged to give the worm one complete rotation during each such transmitting operation. As will be explained 125 presently, when the watchman has reached 130

the last station of the last tour, and at that station has operated his transmitter, shifting lever 16^a is disengaged from the worm, and restored to initial position, thereby restoring wheel 16 to initial axial position.

It remains to describe various features which, for the sake of simplicity of description, have been passed over heretofore.

In order that the watchman may advance the registering mechanism one step only at each engagement with a key-device, provision is made to disengage ratchet pin 20 from ratchet wheel 21 immediately upon release of button 17 after one registration has been effected, and to keep that pin out of engagement with that ratchet wheel if the button 17 be pressed in again before the key-device and the box have been disengaged. To this end, the cam 19 carrying pin 20 is pivoted at 19^a, and has a cam-edge 19^b, adapted to coact with a pin 19^c, also cam-edges 19^d and 19^e (the latter beveled as shown in Fig. 8^e) adapted to coact with a spring-actuated pin 19^f. When, in normal operation, (the parts being then in the positions shown in Fig. 6), button 17 is pressed in, engagement of cam-edge 19^d with pin 19^c causes cam 19 to turn about its pivot, bringing pin 20 into engagement with a tooth of ratchet-wheel 21. These teeth are hook-shaped, as shown, and once the pin 20 is engaged with one of said teeth it will be held in engagement therewith during further inward movement of button 17; which movement results in advancing the ratchet wheel through the space of one tooth. At any time during this inward movement of the button 17, and until that movement is complete, release of the button 17 will permit that button to move out again and will permit the parts of the registry mechanism to return to the positions occupied before the button 17 was pressed in, no registration having been effected; but once the button 17 has been pressed in completely, pawl 21^b engages a further tooth of ratchet wheel 21^a, and then, when button 17 is released, and moves out again, a spring 19^g moves cam 19 about its pivot so as to disengage pin 20 from ratchet wheel 21. Before the outward motion of button 17 is complete, it is arrested by engagement of a pin 17^a carried by the shank of that button, with a spring-actuated tooth 27^c carried by the lever 27^a connected to bar 27. When button 17 is pressed inward from its extreme outer position, this tooth 27^c yields to permit passage of pin 17^a; but during the return of said button 17 said tooth engages said pin 17^a and so arrests said button 17 with the cam 19 in such a position that if the button 17 be pressed in again pin 20 will not engage ratchet wheel 21. This is the position of the parts shown in Fig. 8. In order that pin 20 may engage ratchet wheel

21 it is necessary that cam 19 be moved so that pin 19^f engages cam edge 19^a. This cannot occur until the box is pulled away from that key-device with which it has been in engagement, whereupon bar 27 will move to the left (of Figs. 1 and 13) and the consequent motion of lever 27^a carries the tooth 27^c out of engagement with pin 17^a (as shown particularly in Fig. 7), permitting button 17 to continue its outward movement; during which movement, beveled cam edge 19^e depresses pin 19^c, cam 19 then passing over the top of pin 19^c until that pin, rising again, engages cam edge 19^a. The parts are then in normal position, and are ready for a further registration operation when, and only when, the box has been applied to the key device next in series, so moving bar 27 into position to release wheel 16, raising from wheel 15 the tumblers previously engaged therewith, and moving arm 27^a inward so that its tooth 27^c is in position to engage pin 17^a.

It will be seen that tooth 27^c and pin 17^a and associated parts constitute a species of escapement, operated by engagement with and disengagement of the box from the various key devices, and operating to permit connection of the actuating button 17 to the registering mechanism proper once, and once only, for each engagement of the box with any particular key device.

Lock-wheel 15 is advanced, step by step, against the torsion of a spring 22^a connected to the shaft 22 of said wheel 15. When the wheel 15 has been advanced through a full cycle there is, opposite pin 20, a blank space 21^d (see Fig. 6) on ratchet wheel 21. Pressing in button 17 at this point does not cause further advance of the registering mechanism, therefore, but does no harm. The watchman, having now reached the end of the tour over which he has been passing, should plug into the signal circuit by means of his plug 39, if there be a contact socket C at that point, and having done so, or, in any case, should operate his transmitter handle 14. The signal wheel 11 of the transmitter, in its consequent rotation, will engage, by means of its pin 11^a, the tail 21^e of pawl 21^b, so disengaging that pawl from ratchet wheel 21^a, and permitting spring 22^a to turn wheels 21 and 15 back to starting position. During the operation of the transmitter, worm shafts 16^a will be rotated, so causing shifting lever 16^a to move wheel 16 one step to the left (of Fig. 1), so conditioning the box for registrations at the key devices of the next tour of the series.

Provision is made for returning the shifting lever 16^a, and with it the wheel 16, to initial position, when the end of the last tour has been reached. To this end lever 16^a is provided with a lip 16^f (see Fig. 12) which will be engaged and lifted by a pin 16^g on

one of the gears 16^e, when the transmitter is operated at the end of the last tour of the series. Thereby shifting lever 16^a is disengaged from the worm 16^c, and is returned 5 to initial position by a spring 16^h, being arrested at the proper point by an adjustable stop 16ⁱ; and when so arrested, it drops into engagement with the worm 16^c. In so re-turning, the lever 16^a carries wheel 16 back 10 to starting position.

The return means just described is operative when the last tour contains the same number of stations as do the preceding tours. In some cases, however, it is convenient 15 that the last tour contain a less number of stations than do the preceding tours. For such cases, the box is provided with additional return mechanism, as follows: The locking wheel 15 is provided with a pin 15^a, 20 which may be located at one or another of various positions on said wheel, according to the number of stations in the last tour. During the rotation of wheel 15 as the watchman passes from station to station in 25 each tour, the pin 15^a is caused, at a certain point in such rotation, to engage the slot 15^b of a pivoted cam 15^c and so to move said cam about its pivot; after which, if the wheel 15 be advanced still further, the pin 30 15^a moves out of engagement with said cam. On the return motion of wheel 15, pin 15^a returns cam 15^c to first position. During all of the tours except the last tour of the series, these motions of cam 15^c are without 35 effect; but during the lateral motion of shifting lever 16^a, as the watchman passes from tour to tour, said lever carries with it laterally a trip member 15^d (see particularly Fig. 12) which is movable axially as 40 well as rotatably; and at the beginning of the last tour, this trip member 15^d is in the path of the cam 15^c. The parts being in this position, when cam 15^c is actuated by pin 15^a, said cam actuates trip 15^d (this will 45 occur while the watchman is registering his visit to the last station of the last tour), causing said trip to raise a pivoted lever 15^e having a horizontal member 15^f engaged by a lug 16^k of the shift lever 16^a; whereby 50 said shift lever 16^a is raised out of engagement with the worm 16^c, and is returned by spring 16^h against stop 16ⁱ, said shift lever being held raised by trip 15^d and member 15^e—15^f until, the transmitter of the box 55 having been actuated at the end of the last tour, a pin 16^m on one of the gears 16^e trips a latch 16ⁿ depending from lever 15^e and which, by engagement with a post 16^o, has hitherto been holding lever 15^e elevated. 60 The shift lever 16^a then drops into engagement with the worm.

Latch 16ⁿ is raised by lever 15^e when the latter is raised by trip 15^d, and thereby a pin 16^p projecting from the latch engages 65 pawl 36^a and moves the same into position

to engage tooth 36^c, so that when the transmitter handle 14 is turned the transmitter spring may be wound. Lever 15^e has a tail which, as shown particularly in Fig. 12, lifts any of the tumblers 10 which may be in engagement with wheel 15 when that lever 15^e is lifted at the end of the last tour. 70

To further facilitate the understanding of the mechanism of the box, and its operation, I will describe briefly what happens 75 as the box is used. As shown particularly in Fig. 14, the several key devices A are arranged in a plurality of groups, each key device representing, in that figure, a particular station which the watchman is supposed to visit; and it is convenient for descriptive purposes, and other reasons, to regard each such group of stations as constituting a separate "tour." At the end station of one or more of these tours a plug- 80 socket C is located, connected to a circuit D leading to a relay E by which the signals may be received. If it be desired that the signals be recorded, this relay may operate 85 a recorder F. 90

Suppose the mechanism of the box be in its initial condition in all respects, and that the watchman approaches the first station of the first tour. He presses his box against the key device of that station; that is to 95 say, he forces the sockets B^b of that box over the pins A^a of the first key-device, and in so doing causes the ends of the key-shanks 1 of that key device to engage the ends of the levers or tumblers 10 of the locking mechanism of the box, so raising clear 100 of notched wheel 15 any of such tumblers which may have been in engagement with notches of said wheel. At the same time, the finger 29^a of the key device engages the corresponding finger 29 of lock-bar 27 and presses said lock-bar inward until its notch 28 registers with notched wheel 16; said notched wheel 16 being now in the position corresponding to the first tour, and the 105 fingers 29^a of the key-devices of the first tour being all of a length to cause the notch 28 to register with the wheel 16 when the latter is in the first tour position. 110

The box being now fully engaged with the 115 first key device, the watchman presses in the button 17, and the pin 20 carried by the cam 19 engages a tooth of ratchet wheel 21 and advances said wheel (wheels 16 and 15 now being free to turn) through the space 120 of one tooth, whereupon locking pawl 21^b engages another tooth of ratchet wheel 21^a, preventing return of wheels 21 and 21^a upon release of button 17. Until button 17 has been pressed in far enough to cause pawl 21^b to 125 engage with a new tooth of wheel 21^a, release of the button 17 would simply permit its return, and with it the parts of the ratchet mechanism actuated by it; but after button 17 has been pressed in far enough 130

so that pawl 21^b engages a new tooth of wheel 21^a, return of the button 17 causes pin 20 to disengage that tooth of wheel 21 with which it has been in engagement, cam 19 moving out under the influence of spring 19^g. During the return movement of button 17, its pin 17^a engages the claw 27^c (see Fig. 8, showing the parts in that position) and thereby the outward movement of button 17 is arrested with the cam 19 in such position that cam edge 19^d is not in engagement with pin 19^f. Therefore, if, with the parts in such position, button 17 be pressed in again, pin 20 will not engage a tooth of ratchet wheel 21, and such inward motion of the button will have no effect on the registration mechanism. In a word, the watchman can actuate his box once only at each station he visits.

20 The registration of the visit to the first station having been completed, the watchman disengages his box from the key device of the first station, and moves on to the second station of the first tour. By 25 the advance of wheel 15, the box has been conditioned for actuation upon engagement with the key device of that second station, and by such second key device only. By the withdrawal of the box from the first 30 key device, lock-bar 27 has been permitted to move out, thereby engaging with a slot of wheel 16, so preventing operation of the registering mechanism, while pin 17^a is disengaged by claw 27^c, the claw moving to 35 the position shown in Fig. 7, button 17 being thereby permitted to move out to its normal position.

When the watchman reaches the second station of the first tour, he engages his box 40 with the key device of that station, and lock-bar 27 is moved in until its notch 28 registers with wheel 16. At the same time, the tumblers 10 in engagement with wheel 15 are lifted out of such engagement. The 45 watchman then presses in button 17, and registers his visit to such second station, wheel 15 advancing so that the box is conditioned for influence by the third key device, and by that third key device only. The box 50 is then disengaged from the second key device, and the watchman proceeds to the third station, where the operations above mentioned are repeated. When the watchman has reached the last station of the first tour, 55 pin 20 is opposite a blank space of ratchet wheel 21, and actuation of button 17 causes no further advance of wheels 15 and 16. But while the box is in engagement with the key device of this last station, the watch- 60 man operates his transmitter handle 14. Arm 24^a of gear 24 is now holding pawl 36^a (Fig. 11) in engagement with claw 36^c, and therefore rotation of handle 14 and shaft 36 causes the winding of transmitter spring 65 13; therefore, upon release of handle 14,

the spring 13 will cause the operation of the transmitter mechanism; and, if the watchman has connected the transmitter plug 39 to the socket C of the transmitter circuit, the characteristic signal of the box will be sent in. During the rotation of the break wheel 11 its pin 11^a will trip pawl 21^b, permitting ratchet wheels 21 and 21^a, and lock wheels 15 and 16 to return to initial position, under the influence of spring 22^a. Also, during the rotation of the break wheel worm 16^d will be rotated, so moving wheel 16 to the left one space, thereby conditioning the box for operation at the stations of the second tour, and at such second tour stations only.

In this manner, the box is operated at the stations of the several tours, until the last station of the last tour is reached. Here shift-bar 16^a is lifted out of engagement with worm 16^e, either by pin 16^g on wheel 16^e, or by actuation of parts 15^a, 15^b, 15^c, 15^d, and 15^e, and the shift-bar is restored to initial position by spring 16^h, carrying with it slotted wheel 16 and trip 15^d; and the parts are then in condition for the watchman to begin his tours again.

It is not necessary that provision be made for the sending of a signal to the central station at the end of each tour; for the sending of a signal from any one of the sockets C indicates that the watchman has visited every station of the entire series since his last visit to the station at which such socket C is located; but as a rule it is preferable for the watchman to signal at the end of each tour. Whether or not there be a socket C at the end of a tour, operation of the transmitter mechanism of the box at the end of that tour will condition the mechanism for the beginning of the next tour.

What I claim is:—

1. A watchman's tour system comprising a plurality of groups of stations, each station having a conditioning device, differing from the other conditioning devices of its group, the conditioning devices of each group having means distinguishing them from the conditioning devices of the other group or groups, in combination with a portable watchman's box adapted to be applied to said conditioning devices successively and comprising registering means adapted to be advanced progressively together with means, affected by such application to the station conditioning devices, to prevent advance of such registering means except as the box is disconnected from one station conditioning device and is applied to another station conditioning device, said watchman's box also comprising means for conditioning said registering means for influence by the station conditioning devices of one group only at any one time, and for

conditioning said registering means for influence by the station conditioning devices of another group after completion of a tour of one group.

5 2. A watchman's tour system comprising a plurality of groups of stations, each station having a conditioning device, differing from the other conditioning devices of its group, the conditioning devices of each group having means distinguishing them from the conditioning devices of the other group or groups, in combination with a portable watchman's box adapted to be applied to the said conditioning devices successively and comprising registering means adapted to be advanced progressively together with means, affected by such application to the station conditioning devices, to prevent advance of such registering means except as 10 the box is disconnected from one station conditioning device and is applied to another station conditioning device, said watchman's box also comprising means for conditioning said registering means for influence by the station conditioning devices of one group only at any one time, and for shifting for influence by the station conditioning devices of another group after completion of a tour of one such group.

15 3. A watchman's tour system comprising a plurality of groups of stations, each station having a conditioning device, different from the other conditioning devices of its group, the conditioning devices of each group having means distinguishing them from the conditioning devices of the other group or groups, in combination with a portable watchman's box adapted to be applied to said conditioning devices successively and comprising registering means adapted to be advanced progressively together with means, affected by such application to the station conditioning devices, to prevent advance of such registering means except as the box is disconnected from one station conditioning device and is applied to another station conditioning device, said 20 watchman's box also comprising means for conditioning the registering means for influence by the station conditioning devices of one group only at any one time, and for conditioning said registering means for influence by the station conditioning devices of another group after completion of a tour of one group, signal transmitting means, and means rendering the same operable only upon the completion of a predetermined tour.

25 4. A watchman's tour signal system comprising a plurality of groups of stations, each station having a conditioning device, different from the other conditioning devices of its group, the conditioning devices of each group having means distinguishing them from the conditioning devices of the other group or groups, in combination with a portable watchman's box adapted to be applied to the said conditioning devices successively and comprising registering means adapted to be advanced progressively together with means, affected by such application to the station conditioning devices, to prevent advance of such registering means except as the box is disconnected from one station conditioning device and is applied to another station conditioning device, said 30 watchman's box also comprising means for conditioning the registering means for influence by the station conditioning devices of one group only at any one time, and for conditioning said registering means for influence by the station conditioning devices of another group after completion of a tour of one group, signal transmitting means, and means rendering the same operable only upon the completion of a predetermined tour.

35 5. A watchman's tour system comprising a plurality of groups of stations, each station having a conditioning device, different from the other conditioning devices of its group, the conditioning devices of each group having means distinguishing them from the conditioning devices of the other group or groups, in combination with a portable watchman's box adapted to be applied to the said conditioning devices successively and comprising registering means adapted to be advanced progressively together with means, affected by such application to the station conditioning devices, to prevent advance of such registering means except as the box is disconnected from one station conditioning device and is applied to another station conditioning device, said 40 watchman's box also comprising means for conditioning the registering means for influence by the station conditioning devices of one group only at any one time, and for conditioning said registering means for influence by the station conditioning devices of another group after completion of a tour of one group, signal transmitting means, and means rendering the same operable only upon the completion of a predetermined tour, and means, operable by said signal transmitting means upon the completion of the last tour, for restoring the registering means to initial condition.

45 6. A watchman's tour system comprising a watchman's box having register mechanism comprising an operating device, a locking wheel adapted to be operated thereby, a locking bar adapted to cooperate therewith, means adapted to be engaged by external conditioning devices and comprising a plurality of locking members adapted to be positioned selectively and a notched locking wheel having selective notches adapted to be engaged by said locking members, said selectively notched locking wheel in driving

a portable watchman's box adapted to be applied to said conditioning devices successively and comprising registering means adapted to be advanced progressively together with means, affected by such application to the station conditioning devices, to prevent advance of such registering means except as the box is disconnected from one station conditioning device and is applied to another station conditioning device, said 45 watchman's box also comprising means for conditioning said registering means for influence by the station conditioning devices of one group only at any one time, and for conditioning said registering means for influence by the station conditioning devices of another group after completion of a tour of one group, signal transmitting means, and means rendering the same operable only upon the completion of a predetermined tour.

50 7. A watchman's tour signal system comprising a plurality of groups of stations, each station having a conditioning device, different from the other conditioning devices of its group, the conditioning devices of each group having means distinguishing them from the conditioning devices of the other group or groups, in combination with a portable watchman's box adapted to be applied to the said conditioning devices successively and comprising registering means adapted to be advanced progressively together with means, affected by such application to the station conditioning devices, to prevent advance of such registering means except as the box is disconnected from one station conditioning device and is applied to another station conditioning device, said 55 watchman's box also comprising means for conditioning the registering means for influence by the station conditioning devices of one group only at any one time, and for conditioning said registering means for influence by the station conditioning devices of another group after completion of a tour of one group, signal transmitting means, and means rendering the same operable only upon the completion of a predetermined tour, and means, operable by said signal transmitting means upon the completion of the last tour, for restoring the registering means to initial condition.

60 8. A watchman's tour system comprising a watchman's box having register mechanism comprising an operating device, a locking wheel adapted to be operated thereby, a locking bar adapted to cooperate therewith, means adapted to be engaged by external conditioning devices and comprising a plurality of locking members adapted to be positioned selectively and a notched locking wheel having selective notches adapted to be engaged by said locking members, said selectively notched locking wheel in driving

65 other group or groups, in combination with

connection with said first-mentioned locking wheel, means for returning said first-mentioned locking wheel and said notched locking wheel to initial position at the conclusion of a predetermined number of operations, and means for moving said first-mentioned locking wheel axially upon each such return, in combination with a plurality of groups of station conditioning devices, 5 each comprising means for operating the locking members of said box selectively and also comprising means for adjusting to a definite position said locking bar, each group of conditioning devices arranged to 10 adjust said locking bar to the same position, which is different from the position to which all of the other conditioning devices adjust said locking bar.

7. A watchman's tour system comprising 20 a watchman's box having register mechanism comprising an operating device, a locking wheel adapted to be operated thereby, a locking bar adapted to coöperate therewith, means adapted to be engaged by external conditioning devices and comprising a plurality of locking members adapted to be positioned selectively and a notched locking wheel having selective notches adapted to be engaged by said locking members, said 25 selectively notched locking wheel in driving connection with said first-mentioned locking wheel, means for returning said first-mentioned locking wheel and said notched locking wheel to initial position at the conclusion of a predetermined number of operations, and means for moving said first-mentioned locking wheel axially upon each such return, in combination with a plurality of station conditioning devices, each 30 comprising means for operating the locking members of said box selectively and also comprising means for adjusting to a definite position said locking bar, each group of conditioning devices arranged to adjust 35 said locking bar to the same position, which is a different position from that to which the conditioning devices of each other group adjust said locking bar, and means for returning said first-mentioned locking wheel 40 axially after visitation of all conditioning devices.

8. A watchman's tour system comprising a watchman's box and a plurality of groups of stations, the said stations and the said box together comprising means whereby for the proper operation of register mechanism in said box the watchman must visit in proper turn the several stations of one certain group, then in proper turn the several 45 stations of another certain group, and so on until all the stations have been visited, said box comprising automatic means whereby after the visitation of the last station of one group said register mechanism is adjusted for operation at the stations of the 50

next group and for operation at the stations of that group only.

9. A watchman's tour system comprising a watchman's box and a plurality of groups of stations, the said stations and the said box together comprising means whereby for the proper operation of register mechanism in said box the watchman must visit all the several stations of one group, then all the several stations of another group, and so on, until all of the stations have been visited, said box comprising automatic means whereby after the visitation of the last station of one group said register mechanism is adjusted for operation at the stations of another group, and whereby after all the stations of all of the groups have been visited said register mechanism is returned to initial position. 70 75 80

10. A registering device comprising register mechanism adapted to register successive actuations of an operating device with which that mechanism is provided, together with locking means for that register mechanism normally preventing operation thereof but adapted to be actuated to release same for operation by application of control means of said locking means to one or another of a series of external conditioning devices, said locking means comprising means adapting it to be influenced by such conditioning means in groups, first by one certain group of such conditioning means and then by another certain group of such conditioning means. 90 95 100

11. A registering device comprising register mechanism adapted to register successive actuations of an operating device with which that mechanism is provided, together with locking means for that register mechanism normally preventing operation thereof but adapted to be actuated to release same for operation by application of control means of said locking means to one or another of a series of external conditioning devices, said locking means comprising means adapting it to be influenced by said conditioning means in groups, first by one certain group of such conditioning means and then by another certain group of such conditioning means, and means for restoring the parts to initial condition. 105 110 115

12. A watchman's box comprising registering means adapted to be advanced progressively together with locking means therefor and control means adapted to be applied to one or another of a series of external conditioning devices and thereby conditioned for operation of said registering means, said box further comprising group control means whereby the mechanism is conditioned first for influence by one certain group only of such external conditioning devices and then by another certain group of such conditioning devices. 120 125 130

13. A watchman's box comprising registering means adapted to be advanced progressively together with locking means therefor and control means adapted to be applied to one or another of a series of external conditioning devices and thereby conditioned for operation of said registering means, said box further comprising group control means whereby the mechanism is conditioned first for influence by one certain group only of such external conditioning devices and then by another certain group of such conditioning devices, and means for restoring the parts to initial condition.

14. A watchman's box comprising registering means adapted to be advanced progressively together with locking means therefor and control means adapted to be applied to one or another of a series of external conditioning devices and thereby conditioned for operation of said registering means, said locking means comprising a plurality of differentiating means adapted to correspond to means differentiating the several conditioning devices of a group of such devices, one from the other, and comprising further group differentiating means, whereby there may be a plurality of groups of such conditioning devices, wherein individual conditioning devices of one group correspond to individual conditioning devices of another group except for group differentiation and whereby after a complete round of operation of the registering means of the box at the several conditioning devices of one group such registering means may be restored, except as to the group differentiation, and operated again at the several conditioning devices of another group.

15. A watchman's box comprising registering means adapted to be advanced progressively together with locking means therefor and control means adapted to be applied to one or another of a series of external conditioning devices and thereby conditioned for operation of said registering means, said locking means comprising a plurality of differentiating means adapted to correspond to means differentiating the several conditioning devices of a group of such devices, one from the other, and comprising further group differentiating means, for differentiating between groups of such conditioning devices, and means for restoring the parts to initial condition after actuation of the registering means at all of the conditioning devices of all of the groups.

16. A watchman's box comprising registering means adapted to be advanced progressively together with locking means therefor and control means adapted to be applied to one or another of a series of external conditioning devices and thereby con-

ditioned for operation of said registering means, said locking means comprising a plurality of differentiating means adapted to correspond to means differentiating the several conditioning devices of a group of such devices, one from the other, and comprising further group differentiating means, for differentiating between groups of such conditioning devices, and means for restoring the parts to initial condition comprising means whereby the parts may be restored notwithstanding that one of said groups contain a less number of conditioning devices than another.

17. A watchman's box comprising registering means adapted to be advanced progressively together with locking means therefor and control means adapted to be applied to one or another of a series of external conditioning devices and thereby conditioned for operation of said registering means, said locking means comprising a plurality of differentiating means adapted to correspond to means differentiating the several conditioning devices of a group one from another, and comprising further means for returning the registering means to initial condition after a round of registering operations.

18. A watchman's box comprising registering means adapted to be advanced progressively together with locking means therefor and control means adapted to be applied to one or another of a series of external conditioning devices and thereby conditioned for operation of said registering means, said locking means comprising a plurality of differentiating means adapted to correspond to means differentiating the several conditioning devices of a group one from another, and comprising further means for returning the registering means to initial condition after a round of registering operations, together with means for causing such return after a less number of registering operations in one such round than in another such round.

19. A watchman's box comprising registering means adapted to be advanced progressively together with locking means therefor and control means adapted to be applied to one or another of a series of external conditioning devices and thereby conditioned for operation of said registering means, normally inoperable signaling means together with means rendering the same operable after a predetermined number of registering operations, and means actuated by said signaling means for returning said registering means to initial condition.

20. A watchman's box comprising registering means adapted to be advanced progressively together with locking means therefor and control means adapted to be applied to one or another of a series of ex-

ternal conditioning devices and thereby conditioned for operation of said registering means, normally inoperable signaling means together with means rendering the same operable after a predetermined number of registering operations, means for returning said registering means to initial condition, means normally preventing such return during a series of registering operations, and means 5 operated by the signaling means in its operation for permitting the action of such return means.

21. A watchman's box comprising registering means adapted to be advanced progressively together with locking means therefor and control means adapted to be applied to one or another of a series of external conditioning devices and thereby conditioned for operation of said registering 10 means, normally inoperable signaling means together with means rendering the same operable after a predetermined number of registering operations, a return spring for said registering means, ratchet mechanism normally preventing return of the registering means, and means operated by said signaling means in its operation for tripping said ratchet mechanism.

22. A watchman's box comprising register mechanism having an operating device, a locking wheel adapted to be operated thereby, a locking bar adapted to coöperate therewith, means adapted to be engaged by external conditioning devices and comprising 30 a plurality of locking members adapted to be positioned selectively and a notched locking wheel having selective notches adapted to be engaged by said locking members, said selectively notched locking wheel in driving 35 connection with said first-mentioned locking wheel, and means for moving said first-mentioned locking wheel axially after a predetermined number of operations.

23. A watchman's box comprising register mechanism having an operating device, a locking wheel adapted to be operated thereby, a locking bar adapted to coöperate therewith, means adapted to be engaged by external conditioning devices and comprising 45 a plurality of locking members adapted to be positioned selectively and a notched locking wheel having selective notches adapted to be engaged by said locking members, said selectively notched locking wheel in driving 50 connection with said first-mentioned locking wheel, means for returning said notched locking wheel to initial position at the conclusion of a predetermined number of operations, and means for moving such first-mentioned locking wheel axially upon each such 55 return.

24. A watchman's box comprising register mechanism having an operating device, a locking wheel adapted to be operated thereby, a locking bar adapted to coöperate there- 60

with, means adapted to be engaged by external conditioning devices and comprising a plurality of locking members adapted to be positioned selectively and a notched locking wheel having selective notches adapted 70 to be engaged by said locking members, said selectively notched locking wheel in driving connection with said first-mentioned locking wheel, means for returning said notched locking wheel to initial position at the conclusion of a predetermined number of operations, means for moving said first-mentioned locking wheel axially upon each such return, and means for returning axially said first-mentioned locking wheel after a plurality of steps thereof.

25. A watchman's box comprising register mechanism having an operating device, a locking wheel adapted to be operated thereby, a locking bar adapted to coöperate therewith, means adapted to be engaged by external conditioning devices and comprising a plurality of locking members adapted to be positioned selectively and a notched locking wheel having selective notches adapted 85 to be engaged by said locking members, said selectively notched locking wheel in driving connection with said first-mentioned locking wheel, the latter being also movable axially, a shifting bar for so moving it, a worm normally engaged by said bar, and means for rotating said worm upon each return of the notched locking wheel.

26. A watchman's box comprising register mechanism having an operating device, a locking wheel adapted to be operated thereby, a locking bar adapted to coöperate therewith, means adapted to be engaged by external conditioning devices and comprising a plurality of locking members adapted to be positioned selectively and a notched locking wheel having selective notches adapted to be engaged by said locking members, said selectively notched locking wheel in driving connection with said first-mentioned locking wheel, the latter being also movable axially, a shifting bar for so moving it, a worm normally engaged by said bar, means for returning said notched locking wheel to initial position at the conclusion of a predetermined number of operations, means for rotating said worm upon each such return of the notched locking wheel, and means for disengaging said shifting bar from said worm and for returning it and the first-mentioned locking wheel after a predetermined number of returns of the notched locking wheel.

In testimony whereof I have signed this specification in the presence of two subscribing witnesses.

RICHARD M. HOPKINS.
